UNITED STATES PATENT OFFICE

MICHAEL H. SULLIVAN, OF POUGHKEEPSIE, NEW YORK.

PISTON AND PISTON-PACKING.

No. 873,806.

Specification of Letters Patent.

Patented Dec. 17,

Application filed April 9, 1907. Serial No. 367,284.

To all whom it may concern:

Be it known that I, MICHAEL H. SULLIVAN, a citizen of the United States, residing at Poughkeepsie, in the county of Dutchess and State of New York, have invented new and useful Improvements in Pistons and Piston-Packings, of which the following is a specification.

My invention is an improved piston and piston packing for steam engines, and it consists in the construction, combination and arrangement of devices hereinafter described and claimed.

One object of my invention is to effect improvements in the means for effecting steam-tight packing between the piston and the cylinder and to minimize friction between them.

A further object is to provide improved means for centering a piston in the cylinder and for preventing the bore of the cylinder from becoming eccentrically enlarged by the friction between it and the piston.

A further object is to provide improved means to prevent the steam rings from turning.

A further object is to provide an improved piston of the built-up type, the parts of which may be readily adjusted and which may be readily assembled and disassembled.

In the accompanying drawings,—Figure 1 is a side elevation of a piston and piston packings embodying my improvements, one of the steam rings and its stop segment being shown in section; Fig. 2 is an end elevation of the same with a portion of the follower plate removed; Fig. 3 is a longitudinal sectional view of the same; Fig. 4 is a transverse sectional view, taken on the plane indicated by the line *a—a* of Fig. 3 and intersecting the bull ring and the inner and outer carrier rings; Fig. 5 is a similar view taken on the plane indicated by the line *b—b* of Fig. 3 and intersecting one of the steam rings; Fig. 6 is a detail elevation of one of the steam rings; and Fig. 7 is a detail perspective view of one of the stop segments.

The piston 1 is of the built-up type, comprising the spider 2, having the flange 3 on one side and the detachable follower plate 4, said follower plate being secured in place by bolts 5. In the annular, circumferential channel 6, around the piston, formed between the flange 3 and the follower plate is a bull ring 7, which has on its periphery a broad central, annular, circumferential chan-

nel 8, and annular, circumferential side grooves 9. The inside diameter of the bull ring is greater than that of the channeled portion of the piston and said bull ring is spaced from the bottom of said channel and adjustably secured concentrically with reference to the piston by adjusting screws 10, which are disposed radially, engage threaded openings in the piston, have their heads bearing against the inner side of the bull ring, and are provided with lock nuts 11. Said bull ring is provided, preferably at points coincident with the center of its channel 8, with radially-disposed screws 12, which operate in threaded openings therein, and the outer ends of which project into said channel 8. Lock nuts 13 are provided for said adjusting screws 12, as shown.

In the channel 8 of the bull ring are inner and outer carrier rings 14, 15. Said inner carrier ring is composed of separate, independently-adjustable segments, which are engaged and adjusted by the screws 12. The outer carrier ring 15 is open on one side and has shouldered overlapping ends 16, which form a lapped joint. Cushioning springs 17, which may be of the form here shown or of any other suitable form are interposed between the inner and outer carrier rings and form a connection between them which is elastic to some extent. The outer carrier ring engages the bore of the cylinder and serves to minimize friction between the piston and cylinder and also to center the piston in the cylinder, such centering being effected by the adjusting screws 12. In the outer sides of the annular flanges of the bull ring, which flanges form the side walls of the channels 8 and 9 are recesses 18.

In each of the side channels 9 of the bull ring is a steam ring 19, open at one side, as at 20. Said steam rings also engage the bore of the cylinder and each has an outstanding lateral flange 21, said flanges of the respective steam rings respectively overhanging the flange 3 of the piston and the edge of the follower plate 4, as shown. In one end of each steam ring, in the side thereof opposed to the proximate flange of the bull ring, is a recess 22. At the bottom of said recess is a notch 23. A longitudinal groove 24 is in the opposite end of each steam ring, in the side thereof which is opposed to the proximate flange of the bull ring. Stop segments 25 have their opposite ends, which lie in different parallel planes, disposed in the recesses

the recesses 18 of the ends of the said ainst the shoulders ne recesses 18, 22, and ents are held against g and serve to prevent turning thereon. The 22nd stop segment which lies in of the steam rings has an lug 26 to enter the notch said steam ring, and the arm or end of which stop segment which lies in the recess 18 of the proximate bull ring flange has a laterally-projecting, longitudinal flange 27 to enter the groove 24 of said steam ring. Said stop rings, in addition to preventing the steam rings from turning, also serve to close the joints at the open sides of said steam rings and hence increase the efficiency of the 20 steam rings and enable them to be the more readily expanded by the steam pressure in the cylinder and caused to effect steam-tight packing between the piston and the cylinder. Moreover, the steam rings can expand and contract without affecting the stop segments or danger of breaking the connections between them and the stop segments.

From the foregoing description, taken in connection with the accompanying drawings, 30 the construction and operation of the invention will be readily understood without requiring a more extended explanation.

Various changes in the form, proportion and the minor details of construction may be 35 resorted to without departing from the principle or sacrificing any of the advantages of this invention, as defined by the appended claims.

Having thus described my invention, what 40 I claim as new, and desire to secure by Letters-Patent, is,—

1. A piston having an annular circumferential channel, a bull ring in said channel and having annular circumferential central 45 and side channels in the outer side, steam rings in the said side channels, a carrier ring in said central channel, means to adjust the bull ring with reference to the piston and means to adjust the carrier ring with reference to the bull ring.

2. A piston having an annular circumferential channel, a bull ring in said channel and having an annular circumferential channel in its outer side, a carrier ring in said 55 channel of the bull ring, means to adjust the bull ring with reference to the piston, and means to adjust the carrier ring with reference to the bull ring.

3. A piston having an annular circumferential channel, a bull ring in said channel and having an annular circumferential channel 60 in its outer side, screws, carried by the piston

to adjust the bull ring, a carrier ring in the said channel of the bull ring, and screws, carried by the bull ring to adjust said carrier 65 ring.

4. A piston having an element provided with an exterior annular circumferential channel and a recess at one side of said channel, an open steam ring in said channel, having a recess in the side opposed to the recessed side of said channel, and a stop element extending across the open side of said ring, lying in the said recesses, and connected to the end portion of said ring. 75

5. A piston having an element provided with an exterior annular circumferential channel and a recess at one side of said channel, an open steam ring in said channel, having a recess in the side opposed to the recessed side of said channel, and a stop element extending across the open side of said ring, lying in the said recesses and secured to one end portion of the ring and slidably secured to the other end portion of the ring to 80 permit contraction and expansion of said ring. 85

6. A piston having an element provided with an exterior annular circumferential channel and a recess at one side of said channel, an open steam ring in said channel, having a recess in the side opposed to the recessed side of said channel, and a stop element extending across the open side of said ring and lying in the said recesses, said ring 90 having a notch in its inner side near one end, and a longitudinal slot in its other end, and said stop element having a lateral lug to enter said notch and a lug to enter and play longitudinally in the said slot as said ring 95 contracts and expands. 100

7. A piston having an annular circumferential channel, a bull ring in said channel and having an annular circumferential exterior channel, means to adjust said bull ring, inner and outer carrier rings in said bull ring channel, a yielding expansion element between said inner and outer carrier rings, and means to adjust said carrier rings. 105

8. A piston having an annular circumferential channel, a bull ring in said channel and having an annular circumferential channel in its outer face, means carried by the piston to adjust the bull ring, a carrier ring in the said channel of the bull ring, and means carried by the bull ring to adjust said carrier ring. 110 115

In testimony whereof I have signed my name to this specification in the presence of two subscribing witnesses.

MICHAEL H. SULLIVAN.
